UNITED STATES PATENT OFFICE.

ARTHUR R. HAVENER, OF WAYLAND, MASSACHUSETTS, ASSIGNOR TO JUDSON L. THOMSON M'F'G CO., A CORPORATION OF MASSACHUSETTS.

RIVET AND CAP SETTING MACHINE.

1,276,652.

Specification of Letters Patent. Patented Aug. 20, 1918.

Application filed March 4, 1918. Serial No. 220,193.

To all whom it may concern:

Be it known that I, ARTHUR R. HAVENER, a citizen of the United States, residing at Wayland, in the county of Middlesex and 5 State of Massachusetts, have invented new and useful Improvements in Rivet and Cap Setting Machines, of which the following is a specification.

This invention relates to a machine for 10 attaching articles to sheet material by means of rivets clenched in rivet caps. The machine is particularly adapted for use in riveting the clasps and hasps of buckles to raincoats, overshoes and other garments.

15 The object of the invention is to provide a light, simple and easily operated machine which can be moved around from one place to another in a shop with very little difficulty and which will combine certainty and 20 speed of operation with durability and strength.

The invention consists in the combinations of mechanisms hereinafter set forth and 25 particularly pointed out in the claims whereby the rivet feeding and setting instrumentalities and the cap feeding and setting instrumentalities are all operated from a single crank, eliminating all rotary cams and thus very much simplifying the 30 machine as well as providing a machine which runs easily and noiselessly and with comparatively little wear on the different parts thereof.

35 The improved means whereby the rivet caps are separated one by one from a column of rivet caps on an inclined portion of the raceway and forced onto and along a horizontal portion of said raceway and subsequently fed to the anvil is made the subject 40 matter of a divisional application, filed by me on June 17, 1918, Serial No. 240,403. The clutch and rivet cap hopper, while being shown in the drawings and described in the specification, are each made the subject 45 matter of a separate application for Letters Patent filed by me of even date herewith.

The invention further consists in the combination and arrangement of parts set forth in the following specification and particularly pointed out in the claims thereof.

Referring to the drawings:

Figure 1 is a front elevation of my improved rivet and cap setting machine.

Fig. 2 is a side elevation viewed from the

left of Fig. 1, a hopper and a spring being 55 broken away.

Fig. 3 is a side elevation viewed from the right of Fig. 1.

Fig. 4 is a sectional elevation taken on line 4—4 of Fig. 1 looking toward the right 60 in said figure.

Fig. 5 is a rear elevation of the machine.

Fig. 6 is a sectional elevation taken on line 6—6 of Fig. 5.

Figs. 7, 8 and 9 are detail sectional elevations illustrating the rivet setting operations.

Fig. 10 is a detail plan view of the rivet cap feeding instrumentalities.

Figs. 11 and 12 are plan views similar to 70 Fig. 10 illustrating the cap feeding instrumentalities in different positions.

Fig. 13 is a sectional elevation taken on line 13—13, Fig. 4.

Fig. 14 is a plan view of a buckle hasp. 75

Like numerals refer to like parts throughout the several views of the drawings.

In the drawings, 15 is the frame of the machine. 16 is the anvil, 17 the work-support, 18 the rivet driver and 19 the rivet 80 carrier. 20 and 21 are the two parts constituting the rivet raceway which leads to the rivet carrier 19 from the rivet hopper 22. 23 and 24 are the horizontal and inclined portions of the raceway 25 which feeds the 85 rivet caps from a rivet cap hopper 26 to the anvil.

27 is the main driving shaft of the machine which is rotated by means of a pulley 28 to which is fastened a pinion 29 which meshes into a gear 30 rotatably mounted on the crank-shaft 31. The gear 30 constitutes the driving member of a two-part clutch, the driven member 32 being rigidly fastened to the shaft 31. The driving member 30 is prevented from moving longitudinally upon the crank-shaft 31 by a collar 33 fast to the shaft 31 at one side of said driving member 30 and by the driven member 32 on the opposite side of said driving member. The 95 driving member 30 is provided with pins 34 which engage a dog 35 pivoted at 36 to the driven member 32 and thus rotate the crank-shaft 31, (see Figs. 5 and 6).

When it is desired to rotate the crank-shaft 31 to operate the machine, a slide 37 (Fig. 5) is moved toward the right in said figure to disengage the same from the dog

35 by means of a bell crank lever 133 (Fig. 5) which engages a pin 134 fast to the slide 37 and is operated by means of a treadle rod 135 which leads to a treadle (not shown in 5 the drawings). As soon as this occurs a spring follower 38 moves the dog 35 out into the path of one of the pins 34. The driving and driven members of the clutch are then locked together to rotate the crank-shaft 31.

10 A reciprocatory motion is imparted to the driver 18 by a driver slide 39 which is connected by a pin 40 to a lever 41, (Fig. 4). The lever 41 is pivoted on a pin 42 which is supported in an arm 43 which, in turn, is pivoted to an eccentric stud 44. The eccentric stud 44 has an arm 45 fast thereto by which it can be rotated and said arm has a spring actuated pin 46 slidably mounted in its outer end and adapted to project into any 20 one of the holes 47 in the segmental plate 48, which segmental plate is fastened to the frame of the machine, so that by rotating the eccentric stud 44 to different positions by means of the arm 45 the arm 43 is raised 25 and lowered and consequently the pivot 42 of the lever 41 is raised and lowered. (See Figs. 4, 5 and 13).

The lever 41 is connected at its rear end by a pin 49 to a member 50 which, at its lower 30 end, is mounted upon the crank 51 of the shaft 31.

The member 50 consists of two parts 52 and 53 having screw-threaded engagement 35 with each other, whereby the length of said member 50 may be increased or diminished as desired. The part 52 is slotted at 54 to receive the circular shaped end 55 of a bell crank lever 56 which is pivoted at 57 to the frame of the machine and the vertical arm 40 58 of which engages an ear 59 on a slide 60.

The slide 60 is provided with an inclined lower edge 61 which engages a roll 62 journaled upon a lever 63 which is pivoted at 64 to the frame of the machine, and terminates in a circular shaped end 65 which projects into a slot 66 extending transversely of the anvil 16. Said anvil is arranged to slide vertically in a sleeve 67 fast to the frame of the machine.

50 The ear 59 is held against the vertical arm 58 of the bell crank lever 56 by a spring 68 which is connected to an arm 69 fast to the slide 60, so that the slide 60 is carried forward by the spring 68 and backward by the 55 arm 58. The distance to which the slide 60 can be moved forward is limited by a screw 70 which, when the slide has arrived at its extreme forward movement, engages the frame of the machine.

60 The rivet caps are deposited in mass in a hopper 26 and are fed from said hopper down the inclined portion 24 of the raceway 25 until the lowermost rivet cap 72 on said inclined portion 24 rests against the upper 65 edge of the slide 60, as illustrated in Fig. 10.

A rivet cap detent and feed finger 73 consists of an arm 74 which is pivoted at 75 to the frame of the machine and terminates in an inclined portion 76 at its forward end, said inclined portion 76 being adapted to be 70 engaged by the front edge of the slide 60 as said slide is moved forward.

A plate 77 is fastened to the arm 74 and said plate has a lateral wedge-shaped projection 78 thereon which is adapted to enter 75 between the lowermost rivet cap 72 on the raceway 25 and the next to the lowermost rivet cap 79 on said raceway, so that said projection 78 acts as a wedge to force the cap 72 from the inclined portion of the raceway 20 along the horizontal portion thereof after the slide 60 has retreated sufficiently to allow this to be done, as hereinafter more fully described, and at the same time the next to the lowermost rivet cap 79 is held 35 against movement downwardly on the inclined portion of the raceway by the projection 78 on the plate 77.

A spring 80 is connected at one end thereof to a pin 81 and at the other end thereof to a pin 82 bearing against the frame of the machine. Said pin 81 constitutes a stop pin to limit the distance to which the arm 73 can be moved by the spring 80 and when the parts are in the relative positions illustrated 95 in Fig. 10 the free end of the arm 74 rests against the side of the slide 60.

The raceway 25 consists of an inclined portion 24, and a horizontally disposed portion 23 formed by two parallelly disposed 100 members 83 and 84 which have a space 85 therebetween. These members 83 and 84 are each grooved at 86 and 87, respectively, upon their inner adjacent faces to receive the opposite sides of the rivet caps as they are fed 105 along the raceway. The raceway 25 terminates at its front end in two fingers 88 and 89 pivoted at 90 and 91, respectively, to the frame of the machine, and terminating at their front ends in segmental circular shaped 110 recesses 92 and 93 into which the rivet cap is fed when in its forward position by the slide 60.

The work-support 17 has a projection 94 thereon, constituting a stop, against which 115 the fingers 88 and 89 abut when in the position illustrated in Fig. 10. Said fingers are moved toward each other by springs 95 and 96, respectively.

The rivet carrier 19 consists of two jaws 120 97 and 98 supported by springs 99 and 100 from a slide 101. The jaws 97 and 98 are recessed to form a pocket 102 adapted to receive a rivet and hold it suspended by the head thereof in a manner well known to 125 those skilled in this art. The slide 101 has a reciprocatory motion imparted thereto by a lever 103 pivoted at 104 to the frame of the machine. The front end of the lever has a pin 105 fast thereto and connected by 130

a spring 106 to a plate 107 fast to the slide 101. A notch 108 is provided in the upper edge of the lever 103 at its outer end and this portion of the lever 103 engages a pin 109 which projects through a slot 110 in a plate 111 fast to the frame of the machine, see Figs. 1 and 2.

The rear end of the lever 103 bears against a roll 112 (see Fig. 5) which is journaled 10 to rotate upon a pin 113 fast to a downwardly depending arm 114, said arm being clamped to the part 53 of the member 50. Thus a reciprocatory motion is imparted to the slide 101 and the rivet carrier 19. The 15 distance to which the slide 101 can be moved downwardly by the lever 103 is regulated by a stop screw 124 which is arranged to abut against the frame of the machine when the slide 101 is in its lowermost position, 20 it being understood that the lower edges of the jaws 97 and 98 of the carrier 19 are intended to stop when in their lowermost position very slightly above the upper surface of the buckle hasp which is being riveted to the sheet material. The extent to which 25 said slide 101 can be moved upwardly is regulated by a stop pin 129 fastened to the slide 101 and adapted to engage a stop screw 130 (Figs. 1 and 2) when the slide 101 is 30 in its uppermost position. The lever 103 at its rear end is provided with an upwardly extending arm 131 which is connected by a spring 132 to the pin 113 upon which the roll 112 is journaled, so that after the pin 35 129 in the slide 101 engages the stop 130, if there is any further downward movement of the roll 112 and the pin 113 the spring 132 will yield, and on the other hand at the end of the downward movement of the slide 101, 40 if there is any further downward movement of the lever 103 at its forward end the spring 106 will yield.

Referring, now, to Figs. 1, 2 and 3, the hopper 22 has a rotary member 115 to which 45 a rotary motion is imparted by a pulley 116, a belt 117 and a pulley 118 formed by a groove in the hub of the driven member 32 of the clutch and the rivets are separated and fed one by one from the part 20 of the 50 raceway to the part 21 by a slide 119 which is operated by a lever 120 pivoted at 142 to the frame of the machine, said lever having a pin 143 extending laterally therefrom to which one end of a spring 121 is attached, 55 the other end of said spring, which is shown broken in Fig. 3, being attached to the slide 119. The pin 143 abuts against the right hand end of the slide 119 (Fig. 3) and a spring 144 is connected at one end to the 60 lever 120 and at the other end to the frame of the machine (Fig. 2).

The lever 120 is rocked by said spring 144 in one direction and is rocked in the opposite direction by a pin 123 which is fastened 65 to the lever 103 and engages a cam plate

122 on the upper end of the lever 120. Thus it will be seen that the slide 119 is moved toward the left (Fig. 3) to feed a rivet from the part 20 of the rivet raceway to the part 21 thereof by the lever 120 and pin 143 which abuts against the right hand end of said slide. The slide is moved in the opposite direction or toward the right, Fig. 3, by the lever 120 through its connection with said slide by the spring 121.

It will thus be seen that should any obstruction to the movement of the slide 119 occur the slide will stop as it is moved yielding in one direction through the spring 121 and in the other direction by the spring 144.

The rivets pass down the part 21 of the rivet raceway and into the pocket 102 in the rivet carrier 19 ready to be inserted in the goods. The rivet caps are fed from the 85 hopper 26 to the raceway 25 by mechanism forming the subject matter of one of the applications hereinbefore referred to, and said mechanism is operated by a shaft 125 driven by a pulley 126 which is rotated by 90 a belt 127 driven by a pulley 128 fast to the shaft 27.

The general operation of the machine hereinbefore specifically described is as follows: The rivets are placed in mass in the 95 hopper 22, the rivet caps are placed in mass in the hopper 26 and assuming the different parts of the machine to be in the relative positions illustrated in the general views of the drawings and in Fig. 10 and that a rivet 100 136 has been fed into the rivet carrier 19 and a rivet cap 140 has been fed over the anvil 16, as illustrated in Fig. 4 in a manner hereinafter more fully described, the operator places the material 137 on the work-support 105 17 and holds the buckle hasp 138 up against the lower end of rivet carrier 19, with the rivet 136 projecting into one of the holes 139 in said buckle hasp. He then throws the clutch into operation by operating the 110 treadle to move the rod 135 (Fig. 5) downwardly, thus rocking the bell crank lever 133 and, through the pin 134, moving the clutch slide 37 toward the right, thus disengaging the left hand end of the clutch slide 37 from the dog 35. The spring follower 38 then causes the dog 35 to be moved to the position illustrated in Fig. 6 and said dog is then engaged by one of the pins 34 on the 115 driving member 30, and the driving member 32 moving in the direction of the arrow *a* (Fig. 6) causes the driven member 32 to be driven in the same direction and to thus rotate the crank shaft 31.

The crank shaft 31, rotating in the direction of the arrow *b* (Fig. 4) causes the bell crank lever 58 to move the slide 60 rearwardly until the front end of said slide disengages the free end of the arm 74 (see Fig. 10) and said arm will then be moved by the 125 130

spring 80 to the position illustrated in Fig. 11, with the wedge-shaped projection 78 projecting between and pressing against the lowermost rivet cap 72 on the inclined portion 24 of the raceway 25 and against the next to the lowermost cap 79 on said raceway. The lower edge of the lowermost rivet cap 72 is now bearing against the upper edge of the slide 60. Upon a further movement of said slide 60 toward the rear the upper edge of said slide will become disengaged from the rivet cap 72 and the spring 80 will then cause the arm 74 to spring forwardly into the position illustrated in Fig.

15 12 and thus drive the rivet cap 72 forward onto and along the horizontal portion 23 of the rivet cap raceway, while at the same time the projection 78 holds the rivet cap 79 and the column of rivet caps above the same 20 against movement on the rivet cap raceway.

During this rearward movement of the slide 60 the incline 61 on the lower edge of said slide engages the roll 62 and rocks the lever 63 to raise the anvil 16 from the position illustrated in Figs. 4 and 7 to that illustrated in Fig. 8, and at the same time the member 50 rocks the lever 41 to move the driver slide 39 and driver 18 downwardly and simultaneously the arm 114 with the roll 30 112 rocks the lever 103 to move the carrier slide 101 and the carrier 19 downwardly until the stop screw 124 engages the frame 15, whereupon further downward movement of the carrier will cease, and the driver will 35 continue its downward movement. The anvil has now been moving upwardly from the position illustrated in Fig. 7 to the position illustrated in Fig. 8 and has forced the fingers 88 and 89 apart and carried the rivet cap 140 with it upwardly and against the lower surface of the material 137 to which the buckle hasp 138 is to be attached. The parts are now in the position illustrated in Fig. 8.

45 Upon further downward movement of the driver 18, the rivet is driven through the buckle hasp 138 and through the material 137 and its points entered in the rivet cap 140 and clenched therein, as illustrated in Fig. 9. At this point in the series of operations the crank 51 is in its uppermost position and upon further rotation of the shaft

31 it will commence to move downwardly and the motions of the different parts hereinbefore described will be reversed, that is, the rivet carrier and rivet driver will move upwardly, the anvil will move downwardly, the fingers 88 and 89 will be brought toward each other by their respective springs until 55 60 they engage the stop 94 and the bell crank lever 58 will be rocked to allow the slide 60 to be moved forward by the spring 68 until the front end of said slide 60 engages the inclined end 76 of the arm 74 and pushes said 65 arm out of the raceway slot, whereupon the

projection 78 will be removed from engagement with the rivet cap 79 and said rivet cap will then slide down the inclined portion of the rivet cap raceway until its lower edge engages the upper edge of the slide 60. Meantime, the rivet cap 72, which has been forced onto and along the horizontal portion 23 of the raceway 25, will be engaged by the front end of the slide 60 and fed forward between the fingers 88 and 89 until it lodges in the segmental circular recesses 92 and 93 on the front end of the fingers 88 and 89 and in alignment with and between the anvil 16, the driver 18 and the rivet carrier 19.

The slide 60 will then be moved back to the position illustrated in Fig. 4 and the operator having released the treadle, the dog 35 will engage the slide 37 and be thrown out of engagement with the driving member of the clutch, whereupon the machine will 25 come to a stop. The buckle hasp is then moved, by the operator, together with the material, to insert a rivet in the other hole 141 thereof in the same manner as hereinbefore described in relation to the insertion of 90 a rivet in the hole 140.

If desired, instead of placing the material 137 on the work-support 17 and holding the buckle hasp 138 up against the lower end of the rivet carrier 19, with the rivet 136 projecting into one of the holes 139 in said buckle hasp at the beginning of the operation of the machine, the operator may place the buckle hasp 138 against the material 137 and hold them up together against the lower 100 end of the rivet carrier, with the rivet 136 projecting into one of the holes 139 in said buckle hasp. Then, when the machine is operated as hereinbefore described, the carrier 19 will move downwardly until the stop-screw 124 engages the frame 15 and the parts, together with the buckle hasp and material, assume the relative positions illustrated in Fig. 8, whereupon further downward movement of the carrier will cease and 110 the driver will continue its downward movement to drive the rivet through the buckle hasp and material and clench it in the rivet cap, as illustrated in Fig. 9.

Having thus described my invention, what 115 I claim and desire by Letters Patent to secure is:

1. A rivet and cap setting machine having, in combination, rivet setting instrumentalities comprising a rivet holder and a 120 rivet driver, rivet cap setting instrumentalities comprising an anvil in alignment with said driver, and a holder for a rivet cap interposed between said rivet holder and anvil, a driving shaft, a crank on said shaft 125 and mechanisms operated by said crank whereby reciprocatory motions are imparted to said rivet and cap setting instrumentalities to drive a rivet through a piece of sheet material and clench it in said cap. 130

2. A riveting machine having, in combination, an anvil, a rivet carrier, a driver in alinement with said anvil and carrier, a driving shaft, a crank on said shaft and mechanisms operated by said crank whereby reciprocatory motions are imparted to said carrier and driver toward and away from said anvil. 70
3. A riveting machine having, in combination, an anvil, a rivet carrier, a driver in alinement with said anvil and carrier, a driving shaft, a crank on said shaft, mechanism adapted to impart a reciprocatory motion to said driver comprising a lever and a member connecting said lever to said crank and mechanism adapted to impart a reciprocatory motion to said carrier comprising a lever and an arm fast to said member and engaging said lever. 75
4. A riveting machine having, in combination, an anvil, a rivet carrier, a driver in alinement with said anvil and carrier, a driving shaft, a crank on said shaft, mechanism adapted to impart a reciprocatory motion to said driver comprising a lever and a member connecting said lever to said crank and mechanism adapted to impart a reciprocatory motion to said carrier comprising a lever and an arm adjustably fastened to said member and a roll on said arm engaging said lever. 80
5. A riveting machine having, in combination, an anvil, a rivet carrier, a driver in alinement with said anvil and carrier, a driving shaft, a crank on said shaft, mechanism adapted to impart a reciprocatory motion to said driver comprising a lever and a member connecting said lever to said crank, mechanism adapted to impart a reciprocatory motion to said carrier comprising a lever and a member connecting said lever to said crank, mechanism adapted to impart a reciprocatory motion to said carrier comprising a lever and an arm fast to said member and engaging said lever, a raceway in two parts for feeding rivets to said rivet carrier and mechanism operated by said carrier lever adapted to separate a rivet from a column of rivets on one of the parts of said raceway and carry it to the other of said parts of said raceway. 85
6. A riveting machine having, in combination, an anvil, a rivet carrier, a driver in alinement with said anvil and carrier, a driving shaft, a crank on said shaft, mechanism adapted to impart a reciprocatory motion to said driver comprising a lever and a member connecting said lever to said crank, a pivot for said lever, and means to raise and lower said pivot, whereby the distance of said driver, when at its lowermost point, from said anvil may be varied. 90
7. A riveting machine having, in combination, an anvil, a rivet carrier, a driver in alinement with said anvil and carrier, a driving shaft, a crank on said shaft, mechanism adapted to impart a reciprocatory motion to said driver comprising a lever, a member pivoted to one end of said lever and connected to said crank, a pivotal pin connecting the opposite end of said lever to said driver, an arm located between said driver and said connecting member, to which arm said lever is pivoted, and a stud fast to the frame of said machine upon which said arm is pivoted. 95
8. A riveting machine having, in combination, an anvil, a rivet carrier, a driver in alinement with said anvil and carrier, a driving shaft, a crank on said shaft, mechanism adapted to impart a reciprocatory motion to said driver comprising a lever, a member pivoted to one end of said lever and connected to said crank, a pivotal pin connecting the opposite end of said lever to said driver, an arm located between said driver and said connecting member, to which arm said lever is pivoted, a stud eccentrically mounted on the frame of said machine, upon which stud said arm is pivotally mounted and means to rotate said stud and lock the same in different positions, whereby said lever may be raised and lowered together with said driver. 100
9. A riveting machine having, in combination, an anvil, a rivet carrier, a driver in alinement with said anvil and carrier, a driving shaft, a crank on said shaft, a lever engaging said anvil, and a slide movable transversely of said anvil and having an inclined surface adapted to engage said lever and mechanism operated by said crank adapted to impart a reciprocatory motion to said slide, whereby a rocking movement will be imparted to said lever and a reciprocatory movement to said anvil. 105
10. A riveting machine having, in combination, an anvil, a rivet carrier, a driver in alinement with said anvil and carrier, a driving shaft, a crank on said shaft, a lever engaging said anvil, a slide movable transversely of said anvil and having an inclined surface adapted to engage said lever, mechanism adapted to impart a reciprocatory motion to said driver comprising a lever, a member pivoted to one end of said lever and connected to said crank and a bell crank lever, one arm thereof engaging said member and the other arm thereof engaging said slide, whereby said anvil and driver will be reciprocated toward and away from each other. 110
11. A rivet and cap setting machine having, in combination, rivet setting instrumentalities comprising a rivet holder and a rivet driver, rivet cap setting instrumentalities comprising an anvil in alinement with said driver and a holder for a rivet cap interposed between said rivet holder and anvil, a driving shaft, a crank on said shaft, a raceway for rivets leading to said rivet carrier, a raceway for rivet caps terminating between said anvil and rivet carrier, and 115
12. A rivet and cap setting machine having, in combination, rivet setting instrumentalities comprising a rivet holder and a rivet driver, rivet cap setting instrumentalities comprising an anvil in alinement with said driver and a holder for a rivet cap interposed between said rivet holder and anvil, a driving shaft, a crank on said shaft, a raceway for rivets leading to said rivet carrier, a raceway for rivet caps terminating between said anvil and rivet carrier, and 120
13. A rivet and cap setting machine having, in combination, rivet setting instrumentalities comprising a rivet holder and a rivet driver, rivet cap setting instrumentalities comprising an anvil in alinement with said driver and a holder for a rivet cap interposed between said rivet holder and anvil, a driving shaft, a crank on said shaft, a raceway for rivets leading to said rivet carrier, a raceway for rivet caps terminating between said anvil and rivet carrier, and 125
14. A rivet and cap setting machine having, in combination, rivet setting instrumentalities comprising a rivet holder and a rivet driver, rivet cap setting instrumentalities comprising an anvil in alinement with said driver and a holder for a rivet cap interposed between said rivet holder and anvil, a driving shaft, a crank on said shaft, a raceway for rivets leading to said rivet carrier, a raceway for rivet caps terminating between said anvil and rivet carrier, and 130

② mechanisms operated by said crank, viz, a mechanism to feed a rivet cap along said rivet cap raceway and above said anvil, a mechanism to feed rivets down said rivet 5 raceway into said rivet carrier, a mechanism to impart a reciprocatory motion to said anvil, a mechanism adapted to impart a reciprocatory motion to said driver and a mechanism adapted to impart a reciprocatory motion to said rivet carrier, whereby

rivets may be driven through a piece of sheet material and clenched in a rivet cap beneath said sheet material.

In testimony whereof I have hereunto set my hand in presence of two subscribing 15 witnesses.

ARTHUR R. HAVENER.
